UNITED STATES PATENT OFFICE

LURELLE GUILD, OF NEW YORK, N. Y., AND JAMES K. MATTER, OF NEW KENSINGTON, PENNSYLVANIA, ASSIGNORS TO THE ALUMINUM COOKING UTENSIL COMPANY, OF NEW KENSINGTON, PENNSYLVANIA, A CORPORATION OF PENNSYLVANIA

DESIGN FOR A TEAKETTLE

Application filed June 16, 1932. Serial No. 44,102. Term of patent 7 years.

To all whom it may concern:

Be it known that we, LURELLE GUILD and JAMES K. MATTER, citizens of the United States, residing, respectively, at New York, in the county of New York and State of New York, and at New Kensington, in the county of Westmoreland and State of Pennsylvania, have invented a new, original, and ornamental Design for a Tea Kettle, of which the following is a specification, reference being had to the accompanying drawing, forming a part thereof.

The drawing is a perspective view of a tea kettle, showing our new design.

We claim:

The ornamental design for a tea kettle, as shown.

LURELLE GUILD.
JAMES K. MATTER.
